FIRE HOSE WINDING AND TIGHTENING TOOL

Robert Jerauld, 2661 Northrup Ave., and George D. Fator, 3223 Windsor Drive, both of Sacramento, Calif.

Filed July 23, 1962, Ser. No. 71,016

Term of patent 14 years

(Cl. D41—1)

FIG. 1

FIG. 2

FIG. 3

FIGURE 1 is a top plan view of a fire hose winding and tightening tool showing our new design;

FIGURE 2 is a side elevational view; and

FIGURE 3 is a bottom plan view thereof.

We claim:

The ornamental design for a fire hose winding and tightening tool.
